UNITED STATES PATENT OFFICE.

ARTHUR JOSEPH HUNTERFORD POLLEN, OF LONDON, ENGLAND.

FIRE-CONTROL AND GUN-LAYING APPARATUS.

Application filed August 31, 1920. Serial No. 407,105.

To all whom it may concern:

Be it known that I, ARTHUR HUNTERFORD POLLEN, otherwise ARTHUR JOSEPH HUNTERFORD POLLEN, subject of the King of Great Britain, residing at 14 Buckingham Street, London, W. C. 2, England, have invented certain new and useful Improvements in Fire-Control and Gun-Laying Apparatus, of which the following is a specification.

10 This invention relates to improvements in naval fire control and methods of gun laying, and it has for object to provide means whereby fire control may be exercised and guns correctly laid when the target is out 15 of sight, when the target is obscured by a smoke screen, and when the horizon is similarly obscured.

According to this invention a datum mark gyroscopically fixed in space is used in 20 conjunction with range and bearing clocks to give the elevations and bearings to be applied to guns and turrets to enable them to be correctly elevated and trained, as the case may be, upon an invisible target and 25 though the horizon be obscured by an artificial smoke screen or otherwise.

According to one method a datum mark may be created by means of a gyroscopically-controlled beam of light and means 30 provided in connection therewith whereby a turret may be correctly trained and a gun may be correctly elevated, and such datum mark may be shown in the turret at the gun, or it may be at the fire-control position.

35 Such a datum mark may be created in the known manner by means of a source of light in conjunction with a lens or mirror mounted on the casing of a gyroscope or a ring of the gyroscope mounting so that a spot of 40 light is produced.

According to one method one such datum mark from which bearing may be kept is arranged in the turret in combination with means such as an adjustable lubber line 45 whereby the turret may be kept trained in any desired direction by constantly training the turret to keep the spot of light on the lubber line. The lubber line is adjusted in connection with a bearing clock to keep 50 the turret continuously trained on the target.

Another such datum mark from which elevation of a gun may be kept is arranged on the gun in combination with an adjustable index so that the gun may be main-

tained constantly laid to any desired elevation. The index is adjusted in connection with a range clock.

This method of carrying the invention into practice is illustrated by way of example in the accompanying drawings in which Figure 1 is a part elevation part sectional view shewing the application of the invention to a turret, Figure 2 is a detail view of part of Figure 1.

Figure 3 is a sectional plan view of an application of the invention to a gun and Figure 4 is an end elevation of the apparatus.

All the above figures are more or less diagrammatic.

Referring to Figures 1 and 2,

1 represents the floor of the turret within which the gyroscope 2 is located.

The gyroscope 2 which spins around a horizontal axis is mounted in gimbals 3 and 4 which are supported by a bracket 5 fixed to the floor of a casing 6 which is carried by gimbals 7 and 8 mounted upon pedestals 9. The casing 6 therefore remains at an approximately horizontal position irrespective of the roll and pitch of the ship on which the turret is mounted.

When the turret turns in azimuth the casing 6 also turns therewith.

The gyroscope 2 may be driven by compressed air, or electrically, but no means for supplying such motive power are illustrated in the drawings.

A ring 10 is mounted within the casing 6 so that it may be rotated in relation thereto, and carried by a bracket 11 attached to said ring 10 is a source of light such as a projecting lantern 12.

Mounted upon the vertical gimbal ring 4 of the gyroscope is a mirror 13 which receives a beam of light from said projecting lantern 12 and reflects same on to the inner surface of the ring 10, as indicated by dot-and-dash lines, so as to produce thereon a spot (or it may be a line), of light 14 (see Figure 2).

The inside of the ring 10 is provided with a lubber line or fixed index mark 15 (see Figure 2) and said ring may be rotated by any convenient means, such for example, as a hand-operated rack-and-pinion mechanism, 10^a , 10^b or it may be rotated by power driven means.

Initially the angular position of the ring 10 and consequently of the rubber-line 15 is adjusted so that the spot of light 14 coincides with the rubber-line.

5 If the gyroscope 2 is spinning and therefore maintaining its plane of rotation, the outer gimbal ring 4 will have no rotation about its vertical axis, and if the turret is stationary the spot of light 14 will have no 10 movement on the inside surface of the ring 10.

When, however, a movement in azimuth is imparted to the turret, the casing 6, the ring 10 and therefore the source of light 12 15 will change their positions relatively to the mirror 13 and the reflected beam of light and therefore the image 14 will change position in relation to the rubber-line 15.

To bring the image 14 back to correct 20 alignment with the rubber-line 15 the turret is trained until it has the same relative position to the gyroscope plane that it had previously to receiving movement in azimuth.

In order to enable the turret to be trained 25 at a uniform speed for the purpose of synchronizing such training with the rate of change of bearing set up by a moving target or a moving ship, the ring 10 is rotatably mounted within the casing 6 and means, 30 such as rack teeth 10^a and pinion 10^b, are provided for rotating said ring at the required number of degrees per minute.

This rotation may be effected, as already 35 stated by hand, in which case an indicator electrically connected to a suitable transmitter driven by the range and bearing clock would show to the person setting the ring the movement required, or, it may be effected by power, as for example by connecting the 40 ring 10 through suitable gearing to a receiving motor controlled by a transmitter driven by a range and bearing clock and imparting rotation to the ring 10 in agreement with the change of bearing transmitted 45 from said range and bearing clock.

By rotating the turret, by means of the ordinary controlling gear in the opposite direction at exactly the same number of degrees per minute the image 14 is kept in constant relationship to the rubber-line 15.

Similar means may be employed in order 50 to maintain a constant angle of elevation on a gun so that it may be accurately laid upon a target which is not actually visible from the gun position.

This is illustrated in Figures 3 and 4.

16 is the cradle which is mounted so as to turn on the trunnion 17 in the bearing 18.

A table 19 is rigidly secured to the trunnion 17; or, instead of being attached to the trunnion the table 19 may be secured to any portion of the cradle provided that the table is in a plane at right angles to the axis of the trunnion 17.

65 Mounted upon the table 19 there is a plate

or disc 20 which is provided with a centre pin 21 about which said plate or disc may be rotated.

This rotation may be effected by hand, by means of a crank-handle 25 operating a pinion 26 which meshes with gear teeth 27 cut in or attached to the periphery of the plate or disc 20.

The plate or disc 20 carries by means of two brackets 22, 22, and suitable supporting pins 23, 23, a circular casing 24, similar to the casing 6 described above, in which is mounted the gyroscope 2 in its gimbal rings 3 and 4 and spinning about a vertical axis 25.

The casing 24 is weighted so that it normally maintains itself in a vertical plane with the gyro mounting 5 horizontal.

A projecting lantern 12 is mounted within the circular casing 24 and a mirror 13 is carried by the horizontal gimbal ring 4 of the gyroscope 2, and serves to reflect a beam of light on to the inside of the casing 24 which is provided with a rubber-line as in the case of the ring 10 described above.

If owing to roll or pitch the inclination of the gun 26 to the horizon is altered the effect will be to alter the position of the source of light 12 in relationship to the mirror 13 and therefore the image will be displaced relatively to the rubber-line 15 within the casing 24. In order to correct the elevation of the gun the cradle is readjusted about the trunnions 17 until the cradle returns to its original angle of inclination which is reached when the spot of light coincides with the rubber-line.

By means of suitable indicating mechanism the change of range as indicated by the range clock may be applied to the disc 105 or plate 20, by means of the hand-operated gearing, and the elevation of the gun may be synchronized therewith by adjusting the cradle so that the spot of light is maintained in coincidence with the rubber-line.

By means of this invention, fire control may be exercised and turrets correctly trained and guns may be correctly elevated when the target is quite invisible; bearing being applied to a turret and range and bearing being applied to a gun as indicated and the turret trained and the gun laid by means of the datum mark in such a manner that so long as the correct data are transmitted it is possible to maintain accurate fire 115 on an entirely invisible target.

I have described one method of applying this invention in which the datum mark is shown in the turret by means of a spot of light but it may equally be applied at the 125 fire control or director position to give correct bearings and elevations relative to points fixed in the ship for transmission to the turrets and guns.

Other methods of applying the invention 130

will suggest themselves and will be within the scope of my invention as long as a datum mark gyroscopically fixed in space is used in conjunction with range and bearing 5 clocks to obtain the required bearings and elevations.

What I claim is:—

1. Naval fire-control and gun laying apparatus characterized by a datum mark gyroscopically fixed in space, a movable index carried in gimbal mountings and to which, movement representing change of range of an invisible target is applied relatively to said datum mark, and means for adjusting 10 the parts so as to maintain said datum mark and said movable index in coincidence for the purpose set forth.
2. Naval fire-control and gun laying apparatus, characterized by a datum mark gyroscopically fixed in space, a movable index carried in gimbal mountings, and driving means imparting to said movable index movement representing change of bearing of an invisible target applied to it relatively to 20 said datum mark, said datum mark and said movable index being maintainable in coincidence for the purpose set forth.
3. Naval fire-control and gun laying apparatus characterized by a gun, a datum mark 30 carried upon said gun, gyroscopic means for controlling said datum mark in space, a movable index carried in gimbal mountings and adapted to be displaced relatively to said datum mark, said movable index being capable of receiving displacements representing change of range of an invisible 35

target, and means for adjusting the parts so as to maintain said datum mark and said movable index in coincidence for the purpose set forth.

4. Naval fire-control and gun laying apparatus, characterized by, a turret, a datum mark carried upon said turret, gyroscopic means for controlling said datum mark in space, a movable index carried in gimbal 40 mountings and adapted to be displaced relatively to said datum mark, and driving means imparting to said movable index displacements representing changes of bearing of an invisible target, said datum mark 45 and said movable index being maintainable in coincidence for the purpose set forth.

5. Naval fire-control and gun laying apparatus, characterized by a turret, a gyroscope adapted to spin about a horizontal 50 axis, a mirror carried by the vertical gimbal ring of said gyroscope, a movable member carried in gimbal mountings borne by said turret, an index on said movable member, a source of light carried by said movable 55 member and directed upon said mirror to deflect same on to said movable member to provide a datum mark for bearings, said movable member being capable of receiving displacements representing changes of bearing, and the positions of said index and said datum mark being maintainable in coincidence whereby said turret may be correctly trained on an entirely invisible target.

In testimony whereof I have hereunto set 70 my hand.

ARTHUR JOSEPH HUNTERFORD POLLEN.
